UNITED STATES PATENT OFFICE

144,140

DESIGN FOR A SHOE OR SIMILAR ARTICLE

Jacob Sandler, New York, N. Y.

Application December 13, 1945, Serial No. 124,696

Term of patent 14 years

(Cl. D7—7)

To all whom it may concern:

Be it known that I, Jacob Sandler, a citizen of the United States of America, residing in New York city, county of New York, and State of New York, have invented a new, original, and ornamental Design for a Shoe or Similar Article, of which the following is a specification, reference being had to the accompanying drawing, forming part thereof.

The figure on the drawing is a perspective view of a shoe or similar article showing my new design. The opposite side presents substantially the same appearance as the side shown. The characteristic feature of my design resides in the specific arrangement of the transparent saddle on the specific shoe as shown.

I claim:

The ornamental design for a shoe or similar article, substantially as shown and described.

JACOB SANDLER.
